APPLIANCE FOR RAILROAD CARS

Martin Brandon, Villa Park, Ill., assignor to The
Branco Corporation, Chicago, Ill., a corpora-
tion of Illinois

Application November 1, 1941, Serial No. 417,451

7 Claims. (Cl. 105—369)

This invention relates to improvements in appliances for railroad cars and it consists in the matters hereinafter described and more particularly pointed out in the appended claims.

The conventional means, now in general use for closing the lower part of the side door openings of a railroad car for carrying bulk commodity such as grain, consists of a number of panels built up from a good grade of wood lumber. The panels are wider than the door opening so as to extend laterally beyond the sides of the door opening into overlapping engagement with parts of the sides of the car body and to which they are nailed from the inside of the car. Such panels are relatively expensive. In unloading bulk grain from the car, one or more such panels must be loosened and removed from the car to permit of the flow or other movement of the grain out through a door opening.

The present practice in releasing panels of this kind from a car is to employ a relatively long specially formed, metal lever-like bar and pry the panels from their nailed-on position. Generally, the use of the lever-like bar for this purpose, results in damage to the panels to such an extent as to render them unfit for reuse unless such panels are practically rebuilt. In many instances such panels are either removed by unauthorized persons for the lumber contained therein or they are retained by the employees of the consignees for their own use.

Because of the bulk of such panels, they are usually stored in the open, where they are not only exposed to all kinds of weather conditions, thus resulting in rapid deterioration, but they are also often stolen for use as kindling wood. Therefore, it is obvious that the matter of expense and economic loss in the use of conventional wooden panels of this kind is an item of importance to railroad companies hauling vast quantities of bulk commodity such as grain.

In loading a car with certain commodities, it is often desirable to provide one or more transverse bulkheads in the car adjacent the planes of the sides of the door openings so as to leave an aisle between said door openings. Heretofore in providing such bulkheads, wooden panels similar to those before mentioned were nailed to cleats on opposite sides of the car. In the removal of such bulkheads, the panels were pried from the cleats and this often resulted in such damage to the panels as to require a repair thereof.

One of the objects of the present invention is to provide an appliance for a railroad car, which may be used to provide either a grain door therefor or a transverse bulkhead therefor and which appliance though light in weight, is strong and durable while costing less than the conventional structures used for the same purpose.

Another object of the invention is to provide an appliance adapted for use in pairs in connection with the side door opening of a car for closing the bottom portions thereof and made of such thin sheet material as to have but little resistance in itself to bulging pressure but including parts for connection to like parts of a companion appliance so that said appliances mutually coact in bracing one another to considerably increase their resistance to said bulging pressure.

A further object of the invention is to provide an appliance of this kind which may be readily secured in place across a door opening of a railroad car and this in a manner permitting a quick removal of the same for grain unloading purposes.

Also, it is an object of the invention to provide an appliance of this kind that may be readily handled and is of such a construction as to serve no purpose other than the intended one so that the consignee of the car so equipped, will have no object in retaining the same but will return them to the car after unloading, for reuse.

Again, it is an object of the invention to provide an appliance of this kind which includes an integral part for an engagement with the floor of the car so as to there provide a seal without the necessity of calking operations.

The above mentioned objects of the invention, as well as others, together with the advantages thereof will more fully appear as the specification proceeds.

In the drawing:

Fig. 1 is a perspective view of one form of appliance embodying the preferred form of the invention, and which may be used either as a grain door or a bulkhead for railroad cars.

Fig. 2 is a transverse vertical cross sectional view through the lower part of the body of a railroad car in the plane of the side door opening thereof, to which a set of the improved appliance has been applied to provide so-called grain doors therefor.

Fig. 3 is a longitudinal vertical sectional view through a part of the car body as taken on the line 3—3 of Fig. 2.

Fig. 4 is a view in end elevation, on an enlarged scale, of one of the improved appliances when folded for storage or shipment.

Fig. 5 is a detail horizontal sectional view, on a further enlarged scale, through a part of the structure shown in Fig. 3 as taken on the line 5—5 of Fig. 3.

Fig. 6 is a horizontal sectional view through the body of a railroad box car to which a pair of the improved appliances have been applied to provide transverse bulkheads therein so posi-

tioned as to leave an aisle between the opposite side door openings of the car.

In general, the improved appliance may be used in pairs in a railroad grain car, one for each side door opening therein or may be used individually or in pairs as one or more transverse bulkheads therefor. Each appliance includes a body of sheet material which, for the purpose of economy, is relatively thin and therefore in itself, has but little resistance to the bulging pressure of the grain in the car. Each appliance, however, also includes parts which may be attached to like parts of a companion appliance in a car, or even to a portion of the car itself, the said parts then functioning as a tension mean that braces the appliances and this in a manner amply resisting said bulging pressure.

Referring now in detail to that embodiment of the invention illustrated in the drawing and especially to Fig. 1 thereof: 10 indicates an appliance embodying one form of the invention and which includes a body portion made from a rectangular piece of sheet material such as fibre board or corrugated paper board, of a width greater than that of a side door opening in a railroad car and of the desired height. At the bottom of the body is an integral hinged sealing flap or flange 11, the hinge being formed by a score line 11a, and at each side of the body is an integral hinged sealing flap 12-12 the hinge of each of which is formed by a score line 12a. The body is preferably formed with a plurality of vertically spaced score lines 13-13 which divide that part of the body above the flap 11 into a plurality of horizontal panels, the middle one of which has a height greater than the top and bottom ones as best appears in Figs. 1 and 3. This scoring permits the body to be folded into a compact condition for storage and shipment as shown in Fig. 4.

On one face of the body, I provide a plurality of braces which rigidify the body against bulging under the action of the grain or other commodity in the car. As shown in the drawing, said braces may constitute cleats or strips of wood 14 which may be tacked, nailed or otherwise secured to the body of the appliance 10. Preferably there is one of such braces secured to and extending along the longitudinal median line of each panel before mentioned. The length of said bracing strips 14-14 is preferably less than the width of the car door opening with which the appliance may be associated and in each panel, at or near the top and bottom edges of each cleat 14 are longitudinally spaced pairs of small openings 15-15, best indicated in Fig. 5.

Associated with each cleat 14 is a plurality of flexible tie members 16-16 capable of resisting considerable tension. The mid portion of each tie member is disposed in engagement about the outer face of the top and bottom edges of the cleat while the end portions pass through the openings 15-15 to extend inwardly from the inner face of the body. Thus each appliance is a self-contained unit, ready for application to a railroad car body indicated as a whole at 17.

Such a car body includes a floor 18, and upright sides 19 having a door opening 20 therein. Usually each door opening is defined at the sides by upright side posts 21, the inner face of which is usually arranged flush with the inner face of the associated side 19 of the car.

It is to be understood that when the improved appliances are to be used as grain car doors, one of the improved appliances is employed in connection with each door opening 20 of the car body. In applying said appliances, the same

5 is carried out from inside the car body. One appliance is so positioned with respect to a door opening that end portions of the body, which include the flaps 12-12, extend approximately 10 an equal distance laterally beyond each side post 21 to provide a good overlap upon the adjacent parts of the side 19 of the car, with the score line 11a coincident with the inside corner formed by the sides of the car and the floor and with 15 the flap 11 engaged upon the floor. The flap 11 is nailed to the floor as indicated at 22 and then the end portions of the body including the flaps 12-12 are nailed to the side of the car as indicated at 23. Another appliance is then 20 similarly positioned with respect to the other door opening of the car. This leaves the tie members 16 of both appliances extending inwardly into the car. The workman making the 25 application then connects the like ends of the tie elements of one appliance to the like elements of the other appliance, as best appears at 16x in Fig. 2.

The tie elements are preferably made of metal bands or wires. The ends of the tie elements 30 of both appliances may be joined or connected together in any suitable manner so that when joined they become relatively taut and act as tensioned connecting elements.

35 When the car is loaded with bulk grain 24, as shown in Fig. 2, it is apparent that the pressure thereof on the body of the appliances tends to bulge them outwardly. However, the cleats 14 brace the body of each appliance against this 40 pressure and as the appliances on opposite sides of the car are connected by the tensioned tie elements 16, the appliances coact through the tension members 16 to brace each other against the bulging pressure so that they are held in position 45 in a relatively smooth even condition.

By means of the construction mentioned, each appliance seals the associated door opening 20 against leaking grain and reduces loss in this respect.

50 When it is desired to unload the bulk grain, one or both of the appliances may be pried away from its closure position with the same lever-like tool now used in removing the conventional wooden door for the same purpose.

55 In Fig. 6, a pair of such appliances is illustrated as being used to provide longitudinally spaced bulkheads in the car, with each bulkhead disposed in the plane of the door posts on opposite sides of the car. This leaves an aisle 20a between the door openings 20-20 at opposite sides of the car. In this respect it is pointed out that the distance between the score lines 12a-12a and which define the width of the panels of the body, approximates the inside width of the car body.

60 When the appliances are used as bulkheads in a car body, the flaps 11 and 12 of both appliances are faced or directed toward the associated end of the car and the cleats of said appliances are disposed toward the aisle. The flaps 11 and 12 are then nailed to the sides and the floor respectively of the car and the free ends of the tension members 16-16 are then anchored to a fixed part of the car. This fixed part of the car is illustrated 70 75 in Fig. 6 as being the associated end 19a of the

car and to which said ends of said tension members are nailed as at 25.

When a bulk commodity, such as grain, is loaded into those parts of the car between said appliances and the associated ends of the car, the pressure of said commodity tends to bulge the appliances toward the aisle 20a. This pressure, however, places the members 16-16 under tension so that they hold the body of the bulkheads against said pressure, which tends to bulge them.

The improved appliance is light in weight and is also strong and durable. It costs considerably less than the conventional wooden panels now used for the same purpose. It is proof against leaking grain and may be readily applied to the car. Also, its value for use other than its intended one is so small as to discourage the removal of the appliance from the car when the same is unloaded. As the appliances are capable of being folded for storage and shipment, a considerable amount of storage and shipping space is saved.

While in describing the invention, I have referred in detail to the form, arrangement and construction of the parts involved, the same is to be considered only in the illustrative sense so that I do not wish to be limited thereto except as may be specifically set forth in the appended claims.

I claim as my invention:

1. In combination with a railroad car having a floor and opposed side walls, each with a door opening therein, an appliance closing at least the bottom part of each opening, and embodying therein a body portion of relatively thin sheet material wider than the associated door opening and having end portions extending laterally beyond said opening and attached to the associated side of the car, means carried by the body portion of each appliance for bracing the same against the bulging pressure of the grain in the car, and tension means extending between and connecting the body portions of said appliances together.

2. In combination with a railroad car having a floor and opposed side walls, each with a door opening therein, an appliance closing at least the bottom part of each opening, and embodying therein a body portion of relatively thin sheet material wider than the associated door opening and having end portions extending laterally beyond said opening and attached to the associated side of the car, a plurality of members fixed to the body portion of each appliance for bracing the same against the bulging pressure of the grain in the car, and tension elements extending between and operatively connecting the bracing members of one appliance with the bracing members of the other appliance.

3. In combination with a railroad car having a floor and opposed side walls, each with a door opening therein, an appliance closing at least the bottom part of each opening, and embodying therein a body portion of relatively thin sheet material wider than the associated door opening and having end portions extending laterally beyond said opening and attached to the associated side of the car, a plurality of members fixed to the outer surface of the body portion of each appliance for bracing the same against the bulging pressure of the grain in the car, and tension elements extending through and between the body portions of said appliances and engaged with and connecting the bracing members on said appliances together.

4. In combination with a railroad car having a floor and opposed side walls each with a door opening therein, an appliance closing the bottom part of each door opening and embodying therein a body portion of relatively thin sheet material wider than the associated door opening and having end portions extending laterally beyond said opening and attached to the associated side of the car, the bottom part of said body being formed as an inwardly extending sealing flange that is attached to the floor, along the bottom of the door opening, means carried by the body portion of each appliance for bracing the same against the bulging pressure of the grain in the car, and tension elements extending between and connecting the body portions of said appliances together.

5. In combination with a railroad car having a floor and opposed side walls, each with a door opening therein, an appliance closing the bottom part of each door opening and embodying therein a body portion of relatively thin sheet material wider than the associated door opening and having end portions extending laterally beyond said opening and attached to the associated side of the car, the bottom part of said body being formed as an inwardly extending sealing flange that is attached to the floor, along the bottom of the door opening, a plurality of bracing elements on the outer surface of each appliance, and tension members engaged with the bracing members of said appliances and extending through said body portions thereof and operatively connected together.

6. The combination of a car structure having door openings in opposite sides thereof, appliances for closing the bottom portion of said openings, each including a piece of relatively thin sheet material extending across the associated door opening, each piece of sheet material being wider than the associated door opening and having marginal end portions that project beyond the sides of said door opening and overlap and are attached to the inner face of the associated side of the car, and means extending between and secured to the pieces of sheet material of both appliances and acting as a tension means to limit the outward bulging of said pieces of sheet material of both appliances under the action of the grain in the car.

7. The combination of a car structure having door openings in opposite sides thereof, appliances for closing the bottom portion of said openings, each including a piece of relatively thin sheet material extending across the associated door opening, each piece of sheet material being wider than the associated door opening and having marginal end portions that project beyond the sides of said door opening and overlap and are attached to the inner face of the associated side of the car, means disposed upon the outer face of the piece of sheet material of both doors for bracing the same, and means secured to and extending between the bracing means for the pieces of sheet material of both appliances and acting as a tension means to limit the outward bulging of said pieces of sheet material of both appliances under the action of the grain in the car.
